RAILWAY CAR WALL

Vinton E. Sisson, Winnetka, Ill., assignor to Union Metal Products Company, Chicago, Ill., a corporation of Delaware

Application December 16, 1933, Serial No. 702,700

8 Claims. (Cl. 105—409)

The invention relates to railway cars and more particularly to vertical walls for box or other house cars or open top railway cars, such as hopper cars and gondola cars.

5 The invention is particularly adaptable for use in side walls of railway cars, which walls perform two functions; first, they are the load retaining means, and secondly, they are girders or trusses carrying the major portion of the weight of the 10 lading to the body bolsters from whence it is transferred to the trucks.

An object of the invention is to provide a very light and strong car wall which may be quickly and economically made, installed and repaired 15 and wherein the wall plates thereof may be made in dies on reciprocating presses.

Such walls must be very light, as it is expensive to transport dead weight in a car and such walls must be very strong to carry the vertical 20 load as girders or trusses and also to resist the horizontal thrust of plastic lading, such as grain, etc., or of a shifting load. The parts of the wall must be capable of easy assemblage, because 25 replacements frequently are necessary on account of wearing out of parts, corrosion and wrecks.

Another object of the invention is to provide 30 a car wall so that the component parts thereof may be secured together by either bolting, riveting or welding.

In the drawings:

Fig. 1 is a typical application of my device to the side wall of a railway box car.

Fig. 2 is a section on line 2—2 of Fig. 1.

Fig. 3 is a section on line 3—3 of Fig. 1.

35 Figs. 4, 5 and 6 show the relation between the side plate and junction of adjacent side wall sheets.

Fig. 7 is a horizontal cross section through a modified construction.

40 In the form of invention illustrated the upper frame member 2 and the lower frame member 4 may be considered as a side plate and side sill, respectively, of a railway box or house car, or may be considered as a top reinforcing member and side sill, respectively, of a gondola, hopper or other open top car. In either event, they are the upper and lower chords, respectively, of the wall when considered as a girder or truss. The 45 wall plates form the web of the girder and the panels hereinafter described are the stiffeners of the web plate, or when considered as a truss, the panels form the compression members and the plates themselves form the tension members.

50 In the preferred form the wall comprises a plurality of wall plates with their adjacent margins secured together and extending between the upper and lower frame members. These wall plates are secured to the inner side of the upper frame member 2 and to the outer side of the lower 55 frame member 4 to form a shingle construction.

In the preferred form each of said wall plates is provided with an outwardly projecting panel 6 adjacent each of its vertical margins which extend from adjacent the lower part of the upper frame member 2 to and beyond the upper 65 part of the lower frame member 4. Each wall plate is also provided with an inwardly projecting panel 8 preferably extending continuously between the outwardly projecting panels 6 which extend from adjacent the upper part of 70 the lower frame member 4 to and beyond the lower part of the upper frame member 2. The overlapping of the outwardly projecting panels 6 upon the lower frame members 4 strengthens the end of the beam-column at line 10—10 and 75 the overlapping of the inwardly projecting panel 8 upon the upper frame member 2 strengthens 80 the beam-column at line 12—12. The adjacent inner and outer panels preferably merge into each other, as shown in Fig. 7.

The plate is secured to the upper frame member 2 by rivets 20 in the flat marginal portion of the plate in alignment with the side marginal panel 6. The plate is also secured to the upper frame member 2 by the rivets 22 in the marginal portion of the plate in alignment with the central panel 8. The wall plate is secured to the lower frame member 4 in a similar manner. An additional row of rivets (24) are desirable.

85 The total width of the two side marginal panels 6 is preferably substantially equal to the width of the central panel 8 when the panels are of equal depth so that the neutral axis of the paneled plate will be midway between the bounding planes of the side and central panels so as to 90 develop the maximum strength of the metallic plate as a vertical beam. (See Fig. 7 wherein 26 plus 28 equals 30).

95 The wall plate is provided with a flange 32 at one vertical side thereof, which flange is preferably provided with a re-flange 34 to stiffen the flange 32 against buckling. If an interior lining is desired a nailing strip 36 is secured to the flange by the bolt 38 and the lining 40 is nailed to this nailing strip. With this arrangement the bolt 100 does not extend to the outside of the car, thus eliminating a possible leak. The lining is preferably spaced away from the central panel at 42 to prevent sweating of the plate; to allow the plate to dry to prevent corrosion; to give room 105 for grain to fall down to the floor and to allow compressed air to be blown between the plate and the lining for cleaning. Numeral 44 is the floor.

110 The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

VINTON E. SISSON.
